IGNITION AND STEERING LOCK

Irving Knapper, Ossining, N. Y.

Application March 24, 1934, Serial No. 717,250

7 Claims. (Cl. 70—127)

My invention relates generally to means for coincidentally locking the ignition and the steering post of a motor vehicle, and an important object of my invention is to provide a simplified and more efficient arrangement of this type, which is more convenient to operate and affords more reliable protection.

It is also an important object of my invention to provide an arrangement of the type described above which does not require a key for its operation, and therefore eliminates the inconvenience attendant upon loss or misplacement of an ignition key.

Other objects and advantages of my invention will be apparent from a reading of the following description in connection with the drawings, wherein for purposes of illustration I have shown a preferred embodiment of my invention.

In the drawings:—

Figure 1 is a sectional view through the instrument panel showing a portion of the steering column with the device of the invention mounted thereon.

Figure 2 is a sectional view taken approximately on the line 2—2 of Figure 1 and looking downward.

Figure 3 is a perspective view of the locking cylinder.

Figure 4 is a transverse sectional view through the steering column and steering post showing the arrangement of the locking cylinder on the steering post.

Figure 5 is a top plan view of Figure 2 with the dial and switch arm removed.

Figure 6 is a bottom plan view of Figure 5 showing the bottom plate removed, and showing the invention in unlocked position.

Figure 7 is a view similar to Figure 6 showing the device in locking position.

Figure 8 is a transverse sectional view taken through Figure 2 approximately on the line 8—8.

Figure 9 is a transverse sectional view taken approximately on the line 9—9 of Figure 2.

Figure 10 is a transverse sectional view taken through Figure 2.

Figure 11 is a transverse sectional view through Figure 2 taken from the right of Figure 10.

Figure 12 is a transverse sectional view taken approximately on the line 12—12 of Figure 14.

Figure 13 is a bottom plan view of the bottom plate.

Figure 14 is a top plan view of the bottom plate.

Figure 15 is a plan view of the top tumbler disk.

Figure 16 is an edge view thereof.

Figure 17 is a top view of the second tumbler disk.

Figure 18 is an edge view thereof.

Figure 19 is a plan view of the bottom or double tumbler disk.

Figure 20 is an edge elevational view thereof.

Figure 21 is a top plan view of the combination operating plate.

Figure 22 is an edge elevational view of Figure 21.

Figure 23 is a plan view of a washer or wear plate.

Figure 24 is a plan view of a spring washer.

Figure 25 is an edge elevational view of Figure 24.

Figure 26 is an elevational sectional view of the operating knob.

Figure 27 is a plan view of the operating bar.

Figure 28 is an end elevational view of Figure 27.

Figure 29 is a side elevational view of a portion of Figure 27.

Figure 30 is an end view of a member which operates the ignition switch contacts.

Figure 31 is a side elevational view of the fibre cam member shown in Figure 30.

Figure 32 is a plan view of the main bolt operating cam.

Figure 33 is an edge elevational view of Figure 32.

Figure 34 is a plan view of the switch operating arm.

Figure 35 is a vertical longitudinal sectional view taken approximately on the line 35—35 of Figure 34.

Figure 36 is a view of the operating shaft.

Figure 37 is a view of the lower end of the operating shaft.

Figure 38 is a top plan view of the locking dog.

Figure 39 is a side elevational view of Figure 38.

Referring in detail to the drawings the numeral 5 refers generally to the instrument panel of the motor vehicle upon which I mount a generally V-shaped bracket 6 which has an angulated portion 7 formed on its underside with serrations or teeth 8 which are engageable by serrations or teeth 9 on the steering post bracket arm 10 which has the split clamping portion 11 which surrounds the steering column and is clamped thereon by means of the screw 12 which traverses the split as shown in Figure 2. In accordance with my invention the split portion 11 carries a

casing 13 in which the coincidental lock mechanism is contained. The generally rectangular laterally extending casing 13 has a closed top and

5

a removable bottom plate 14. A bolt and nut arrangement 15 traversing the bracket portion 7 and the steering post bracket arm 10 enables adjustably clamping the bracket 10 relative to the bracket 7 so that the steering column 16 may be set at a position convenient to the driver.

Within the steering column 16 is the steering post 17 on which I mount a sleeve or locking cylinder 18 whose form is shown in Figure 3. The locking cylinder 18 has longitudinal notches 19, 20, and 21 circumferentially spaced thereon to be engaged in different positions of the steering post by the head 22 of the locking bolt 23 which passes through an opening 24 in the side of the casing 13 and the side of the steering column 16 for this purpose. It will be obvious that this arrangement permits locking the steering post and hence the steering wheel of the vehicle in any one of three positions. Set screws 25, 26 traverse the opposite sides of the locking cylinder 18 and indent the steering post to lock the locking cylinder in place on the steering post, as shown in Figure 4.

The head 22 is rather long and heavy as shown in Figures 23 and 29 and has a cut out portion 28 which cooperates with one arm 27 of the bolt 23 and is fastened in place by a screw 27' which traverses both the head 22 and the arm 27. The bolt 23 is U-shaped in form and has a relatively elongated bight portion 28 in opposite end portions of which are located slots 29, 30, receiving bolts or screws 31, 32 which depend from the top of the casing 13. Heads 33, 34 on the screws 31, 32 hold the bolt 23 in place so that the same may be slid relative to the bolts or screws 31, 32 in opposite directions to engage and release the dog 22 from the slot in the locking cylinder on the steering post. A spring 35 stretched between a post 36 at the middle of the bight portion of the bolt 23 and an anchor 37 on the wall of the casing adjacent the steering column normally urges the bolt 23 toward the steering column and the dog 22 into engagement with the steering post.

Depending from the top of the casing is a shaft 38 which has a portion flattened at the sides as indicated at 39. This portion 39 is screw-threaded at its lower end as indicated at 40 and below this is a considerably reduced portion as indicated at 41 provided with a rounded lower end as indicated at 42 which is rotatably supported in a depression 43 in the bottom plate of the casing as shown in Figure 9. The upper part 44 of the shaft 38 is rotatably supported in a sleeve portion 45 whose bore portion 46 opens through the top of the casing into a depression 47 in which works the switch arm 48. The upper extremity of the shaft 38 has a reduced part having flat sides entering the generally rectangular hole 49' in the arm 48, and a screw 49 threaded into the upper end of the said upper extremity of the shaft 38 is provided with a washer engaging the top of the arm 48 and holding the arm 48 on the said reduced part so as to rigidly connect the arm 48 with the shaft 38.

Below and rotatably engaging the lower end of the sleeve portion 45 is the main plate portion 51 of the cam 50 which has the elongated central opening 52 receiving the flat sided portion 39 of the shaft 38. This cam as shown in Figures 9, 32 and 33 has a downwardly offset horizontal cam arm 53 for a purpose to be indicated. This cam has also a notch 54 whose purpose will be subsequently described. Supporting the cam 50 in place is the cam 55 which has a cylindrical portion 56 and the cam arm 57. A lock washer

53 below the cam 55 is held in place on the shaft 38 by the nut 59 which is threaded on the threaded portion 40 of the shaft, as shown in Figure 9. The assembly just described is located, as indicated in Figures 6 and 7 at the left hand portion of the casing. To the right of this is the tumbler shaft controlled by the knob, and the switch mechanism, both of which features will be described.

The tumbler shaft which is generally designated 60 is rotatably mounted in a sleeve portion 61 which depends from the top of the casing, and the shaft 60 has on its upper end and resting on a washer 62 engaging the upper side of the top, the dial 63 having the operating knob 64. The shaft 60 has at its lower end a portion 65 whose opposite sides are flattened to mount the tumbler disk operating plate 66 whose construction is shown in Figures 21 and 22. The operating plate 66 has an elongated hole 67 receiving the conformably portion 65 of the shaft 60. A spring washer 69 20 which is shown in Figures 24 and 25 is held up in place by a plate 68 which is in turn held in place by a cotter pin 70 traversing the lower end of the shaft 60, as shown in Figure 8. The operating plate 66 has a dowel or pin 71 on its upper side 25 which is adapted to enter one of the holes 72 in the lower member of the double disk tumbler 73, so as to connect the double disk tumbler for rotation with the shaft 60 by manipulation of the knob 64. The upper disk 75 of the double disk tumbler 30 has a similar arrangement of circumferentially spaced holes 72 and also an upwardly projecting pin 76 located in one of the holes for engaging a pin 79 located in one of the holes 77 of the intermediate tumbler 78 and which depends from the intermediate tumbler 78. From the upper side of the tumbler 78 another pin 80 projects upwardly for engaging with a depending pin 81 on the upper tumbler 84. The upper tumbler 84 is also provided with a circumferentially spaced plurality of holes 83. The upper and intermediate tumblers are rotatable relative to the shaft 60 subject to the engagement of the pins described while the double disk tumbler is connected by the means described for rotation with the shaft 60, so that when the knob 64 is turned the double tumbler will be turned and the upper and intermediate tumblers will turn only when engagement of the pins takes place.

At one side of the casing and at a point intermediate the shaft 38 and the shaft 60 is the shaft 85 which depends from the top of the casing and has rockably mounted thereon the spring urged locking dog 86 which is normally urged in a counterclockwise direction (as viewed in Figures 6 and 7) by the spring 87. The form of this dog is shown clearly in Figures 38 and 39, as generally U-shaped and having a notch 87' in one edge of its bight portion, and the arm 88 on the longer one of its legs. The longer leg 89 is provided with the opening 90 and the shorter leg 91 with the opening 92 for rotatably receiving the shaft 85. The spring 87 has one end anchored to the anchor 93 on the top of the casing and has an intermediate portion circumscribed about the shaft 85 and the opposite end sprung under the bight portion and in the notch 87' so that the dog is urged in the counterclockwise direction.

The arm 88 is arranged to engage the notch 70 54 of the cam 59 in the locked position of the device of the invention, as shown in Figure 7, and the arm 88 is out of the notch 54 only when the bight portion of the dog has entered all of the notches 106, 107, and 108 of the tumbler disks, 75

these notches having been registered by making the proper "combination" by rotating the combination dial. While so engaged with the notches of the tumblers, the dog 86 is in effect disengaged 5 from the cam 50 so that the switch lever 48 can be used to rotate the cam 50 in a counterclockwise direction (as viewed in Figures 6 and 7) for the purpose of working the high point of the cam 50 against the arm 23' of the bolt 23 so as to withdraw the bolt 10 23 from the locked position shown in Figure 7 to the unlocked position shown in Figure 6. The tumblers are prevented from being rotated in any manner while the cam 50 and its switch lever are in the "on" or unlocked position illustrated in 15 Figure 6, by reason of the position of the offset 53 of the cam 50 in the path which the arm 68 of the dog 86 would have to take to withdraw the bight portion from the tumbler notches. When rotated in the clockwise direction the receding of 20 the high point of the cam 50 will permit the locking bolt 23 to be drawn by its spring 35 into engagement with the locking cylinder 18.

The plate 48 forms the circular portion of the ignition switch arm which includes the finger grip portion 49' which carries the spring pressed detent 47' which is arranged to engage either one of the depressions 45' and 46' in the cut-out portion 47 in the top of the casing shown in Figure 5, whereby the switch arm is held in either the "off" or the 25 "on" position until it is desired to shift the same for turning on or turning off the ignition. It will be recognized, therefore, that the shaft 38 is the ignition switch operating shaft and that the ignition switch operating shaft can be operated to the 30 "on" and "off" positions only while the dog 86 is in the position in which it is shown in Figure 6, resulting from the tumblers having first been operated so as to align their notches to receive the 35 bight portion of the dog.

Referring again to the tumbler operating shaft 60 it will be observed that the same is journaled not only in the sleeve 61 but in a sleeve portion 61' which depends from the sleeve portion 61 and has on its exterior a slot 60' with which the tongues 40 66 on wear plates or spacers 95 engage to prevent rotation of the said wear plates. These wear plates are disposed between adjacent ones of the tumbler disks as shown in Figure 8, thereby enabling rotation of any one of the tumbler disks independently 45 of the others within the limits defined by the positions of the various pins.

Mounted on the upper side of the bottom plate 14 as shown in Figure 12 and in Figure 14 is a pair of normally separated spring circuit closing 50 arms 97 and 98, respectively, which are generally L-shaped in form as shown in Figure 12 and have foot portions 99 and 100, respectively, which are 55 rectangular in form and insulated from each other by dielectric washers 101 which are held in place by screws 102. The individual foot portions 99 and 100 are connected to individual binding posts 103 and 104, respectively, which are mounted in the bottom plate 14. A bushing 105 insulates each one of the binding posts from the bottom plate 14, as does an insulating plate 106. The cam arm 57 on the shaft 38 is arranged to engage the spring arm 97 when the switch arm is moved to the "on" position and push the arm 97 into engagement with the arm 98 and thereby 60 close the ignition circuit.

The pins 76, 79, 80, and 81 of the several tumbler disks may be relocated in the holes in the tumblers at will so as to change the combination and their arrangement will cooperate with the 65 notches 106, 107, and 108 of the double tumblers,

the intermediate tumblers and the upper tumbler, respectively, to arrange for the receiving of the bight portion of the locking dog 86 so that the locking dog 86 will be sprung in the counterclockwise direction from the position shown in Figure 7 to the position shown in Figure 6 and thereby release the cam 50 by disengagement from its notch 54, and permitting the cam 50 to be rotated by swinging the ignition switch arm 48. It is obvious that swinging of the switch 10 operating arm 48 clockwise in Figure 2 will operate the cam 50 in such a way as to withdraw the locking bolt 23 from the position shown in Figure 7 to the non-locking position shown in Figure 6. The movement of the cam 50 is accompanied by engagement of the fibre cam 57 with the ignition switch contact 97 and 98, in a manner to engage the contact 97 with the contact 98 and thereby close the ignition circuit.

When the correct combination has been dialed 20 by rotating the knob 64 in opposite directions to three different numbers on the dial, the operating plate 66 will have carried the double disk tumbler into such positions that its upwardly projecting pin 76 will have engaged the depending pin 79 of the intermediate tumbler and thereby placed the notch of the intermediate tumbler in its proper position to receive the arm of the locking dog, and further rotation of the knob 64 will have eventually brought the upper tumbler into 25 position with its notch aligned with the other notches by engagement of the upwardly projecting pin 80 of the intermediate tumbler with the depending pin 81 of the upper tumbler.

To change the "combination" of the tumblers 30 all that is necessary to do is to remove the cotter pin in the lower end of the shaft 60, lift the operating plate away from the double disk tumbler 35 73 so as to disengage the operating plate pin 71 from the hole in the disk 74 and then place the 40 pin 71 in another one of the holes in the disk 74 and then restore the cotter pin in the shaft 60. The mechanism just mentioned is reached simply by removing the bottom plate 14.

It will be observed that while the device is in 45 the unlocked condition shown in Figure 6, the switch arm 48 may be operated to "on" and "off" positions as desired, without upsetting the tumblers, thereby making possible the shutting off the motor while making stops of short duration 50 without locking the steering wheel. However, when desired, the steering wheel may be locked simply by turning the switch arm to the "off" position and then upsetting the tumblers by rotating the knob 64 one revolution, regardless of 55 the position of the steering wheel. One of the notches in the locking sleeve on the steering post may be in such a position at the time of upsetting the tumblers that the locking bolt 23 will immediately engage such notch and lock the 60 steering post, but such a position of the steering post at the time of upsetting the tumblers is not necessary, because the locking bolt is then under tension and will engage the first notch of the locking sleeve on the steering post which may 65 come into place as a result of turning the steering wheel after upsetting the tumblers.

Although I have shown and described herein a preferred embodiment of my invention, it is to be definitely understood that I do not desire to 70 limit the application of the invention thereto, and any change or changes may be made in materials and in the structure and arrangement of parts, within the spirit of the invention and the scope of the subjoined claims.

What is claimed is:—

1. The combination with a steering column enclosing a steering post, of a casing mounted on the steering column, a bolt movably supported in said casing and working through openings provided in the casing and in the steering column and engageable with a part on the steering post, spring means within the casing and urging said bolt toward engagement with said part on the steering post, means for withdrawing said bolt comprising a rotatable cam having a notch in one edge, a plurality of tumbler disks rotatably mounted in the casing each provided with a notch in its edge capable of being registered with the notches of the other disks, a double ended dog rockably mounted in the casing, spring means holding one end of said dog into engagement with the edges of said disks and the opposite end of the dog away from said cam, said opposite end of the dog being arranged to engage with said notch of the cam only while the bolt is in the locked position so as to prevent the cam from being turned, said disks being arranged to be rotated to bring their notches into registry so as to permit said one end of the dog to engage therein and thereby disengage said opposite end from the notch in the cam, and means for rotating said cam while said one end of the dog is disengaged therefrom to operatively engage a part of said bolt so as to withdraw the bolt out of engagement with the steering post.

2. In a device of the character described, a casing, a bolt movably mounted in and having a portion projectable from the casing, spring means engaging said bolt and urging said portion out of the casing into locking position, a cam rotatably mounted in the casing and having a working face engageable with said bolt for withdrawing the bolt into unlocking position against the tension of said spring means, a plurality of combination disks rotatably mounted in said casing, each disk having a peripheral notch, the disks being arranged to be rotated to align the peripheral notches, a double ended dog pivoted on said casing intermediate its ends on said casing, second spring means pressing one end of said dog against the peripheral edges of said disks while their notches are out of alignment and into said notches while the notches are aligned, the opposite end of the dog being arranged to engage in a second notch provided in the periphery of said cam while the said one end of the dog is in engagement with the periphery of said disks so that the cam is positively locked against rotation, the said one end of the dog being arranged to be disengaged from said cam while the said opposite end of the dog is engaged in the aligned peripheral notches of the combination disks so that the cam is free to be rotated, means for rotating said cam in either direction, a normally open switch in said casing, and a second working face on said cam arranged to operatively engage said switch to close the same while said cam is in the bolt withdrawing position.

3. In a lock of the character described a casing having a bolt slidable therein including a portion arranged to project from the casing while in locking position, a cam mounted within the casing operatively engageable with said bolt for withdrawing the bolt into non-locking position and disengageable from the bolt to permit the bolt to return to locking position, a spring normally urging said bolt toward locking position, a set of disk tumblers mounted in said casing, a dog pivoted intermediate its ends on said casing, a

second spring normally urging one end of said dog in a direction to engage with said set of tumblers and the opposite end of the dog in a direction away from with said cam, said cam being provided with a notch, and the periphery of each of the tumblers being provided with a notch, the notches of the tumblers being arranged to be aligned as a result of properly manipulating the tumblers, said one end of the dog being arranged to move into the notches of the tumblers as these notches become aligned and thereby permit said opposite end of the dog to be disengaged from said cam by said second spring and thereby free the cam for movement in different directions for operating said bolt, said cam being provided with a notch arranged to receive the said opposite end of the dog while the cam is in inoperative position and while the first mentioned end of the dog is disengaged from the notches of the tumblers as the tumblers are upset and is riding on the peripheries of the tumblers, the engagement of said opposite end of the dog with the notch of the cam locking the cam in the inoperative disengaged position, wherein the bolt is in the locking position, means for operating said cam, and second means for operating said set of tumblers.

4. A lock of the type described comprising a casing, an extensible bolt mounted on the casing, a spring urging said bolt into extended locking position, a rotatable cam in the casing operatively engageable with said bolt for retracting the bolt, a set of disk tumblers mounted in the casing at one side of said cam, a dog pivoted intermediate its ends on the casing between said cam and said set of tumblers, a second spring urging the adjacent end of the dog toward engagement with said set of tumblers, the opposite end of the dog near the cam being thereby urged away from the cam, each tumbler having a notch arranged to become aligned with the notches of the other tumblers when the tumblers are properly manipulated, so as to receive therein said adjacent end of the dog so that said opposite end of the dog is then disengaged from said cam and the cam is free to be moved in opposite directions to operate said bolt, said cam being formed with a notch arranged to receive the said opposite end of the dog while the said adjacent end of the dog is disengaged from the aligned notches of the tumblers and the tumblers are upset whereby the cam is positively locked in its inoperative position in which the bolt is in its locking position, means for operating said cam, and second means for manipulating the set of tumblers.

5. In combination, a support, a bolt slidable thereon, a spring urging the bolt toward locking position, a notched cam normally disengaged from said bolt so that the bolt is then in the locking position, means for operating said cam into and out of operative engagement with the bolt, a set of normally upset disk tumblers on the support, each formed with a notch, second means for manipulating the tumblers so as to align their notches, spring pressed means normally engaging the periphery of said tumblers and the notch of said cam while the tumblers are upset and the bolt is in its locked position so as to lock the cam in its disengaged position, said spring pressed means being arranged to move into engagement with the notches of the disks when the tumblers are manipulated so as to bring said notches into alignment in a manner to disengage said spring pressed means from the cam and thereby free the cam to be operated by the cam operating means in opposite directions for with- 75

drawing said bolt from and permitting the bolt to return to locking position.

6. In combination, a support, a bolt slidable thereon, a spring urging the bolt toward locking position, a notched cam normally disengaged from said bolt so that the bolt is then in the locking position, means for operating said cam into and out of operative engagement with the bolt, a set of normally upset disk tumblers on the support, each having a notch, second means for manipulating the tumblers so as to align their notches, spring pressed means normally engaging the periphery of said tumblers and the notch of said cam while the tumblers are upset and the bolt is in locking position, so as to lock the cam in its disengaged position, said spring pressed means being arranged to move into engagement with the notches of the disks when the tumblers are manipulated so as to bring their notches into alignment in a manner to disengage said spring pressed means from the cam and thereby free the cam to be operated by the cam operating means in opposite directions for withdrawing said bolt from and permitting the bolt to return to locking position, and stop means on said cam, said stop means being positioned during the operative position of the cam to positively prevent disengagement of said spring pressed means from the aligned notches of the tumblers, thereby preventing upsetting of the tumblers while the bolt is in a retracted position.

7. In combination, a support, a bolt slidable thereon, a spring urging the bolt toward locking

position, a notched cam normally disengaged from said bolt so that the bolt is then in the locking position, means for operating said cam into and out of operative engagement with the bolt, a set of normally upset disk tumblers on the support, each having a notch, second means for manipulating the tumblers so as to align their notches, spring pressed means normally engaging the periphery of said tumblers and the notch of said cam while the tumblers are upset and the bolt is in locking position so as to lock the cam in its disengaged position, said spring pressed means being arranged to move into engagement with the notches of the disk when the tumblers are manipulated so as to bring their notches into alignment in a manner to disengage said spring pressed means from the cam and thereby free the cam to be operated by the cam operating means in opposite directions for withdrawing said bolt from and permitting the bolt to return to locking position, and stop means on said cam, said stop means being positioned during the operative position of the cam to positively prevent disengagement of said spring pressed means from the aligned notches of the tumblers, thereby preventing upsetting of the tumblers while the bolt is in a retracted position, said stop means being arranged to occupy a position while the cam is in its inoperative position in which said stop means engages said bolt in a manner to positively prevent further rotation of the cam away from its operative position.

IRVING KNAPPER.
